EMBORESSED METAL SHEET

Donald H. Campbell, Orchard Park, and Richard Schad, Cheektowaga, N.Y., assignors to Rigidized Metals Corporation, Buffalo, N.Y.

Filed Aug. 5, 1960, Ser. No. 61,635

Term of patent 14 years

(Cl. D54—2)

FIG. 1.

FIG. 2.

FIG. 3.

FIG. 1 is an elevational view looking directly at the face of an embossed metal sheet showing my new design;

FIG. 2 is an elevational view of the opposite face of the sheet of FIG. 1; and

FIG. 3 is a cross-sectional view on the line 3—3 of FIG. 1 on an enlarged scale.

We claim:

The ornamental design for an embossed metal sheet, as shown.
